[57] CLAIM

The ornamental design for a table, as shown and described.

DESCRIPTION

FIG. 1 is a perspective view of a table showing my design;

FIG. 2 is a side view of the table shown in FIG. 1; and

FIG. 3 is a plan view of the table shown in FIG. 1. The bottom of the table is unornamented, and the view of the side opposite that shown in FIG. 2 is identical to the side view shown in FIG. 2.

*FIG. 1.**FIG. 2.**FIG. 3.*
